JAMES L. RAY, OF ESSINGTON, PENNSYLVANIA, ASSIGNOR TO WESTINGHOUSE ELECTRIC & MANUFACTURING COMPANY, A CORPORATION OF PENNSYLVANIA.

BLADE FASTENING.

Application filed September 8, 1924. Serial No. 736,652.

My invention relates to turbines, more particularly to the blade fastening means thereof, and has for its object the provision of apparatus of the character designated which shall be simple of design, easy of manufacture, and which when assembled shall provide a sturdy unitary structure.

The specific object of my invention is to provide, in a turbine having a rotor with 10 undercut grooves for the mounting of blades therein and a widened portion in the groove for the insertion of blades, means for securing a blade mounted in the widened portion of the groove.

15 Apparatus embodying features of my invention is illustrated in the accompanying drawings forming a part of this specification in which Fig. 1 is a perspective view showing a fragment of a turbine rotor having an undercut groove with blades mounted therein and having a widened portion for the insertion of said blades; Fig. 2 is a plan view of a turbine blade mounted in the widened portion of the undercut groove and secured in 20 accordance with my invention; Fig. 3 is a sectional view taken on the line III—III of Fig. 2; and Fig. 4 is an exploded view in perspective of my improved blade fastening means.

25 In the construction of elastic fluid turbines, it has been found desirable in order to secure the moving blades in position, especially where the blades are subjected to high velocities and consequent heavy centrifugal stress, to provide the rotor with some form of undercut groove and to provide blades having root portions fitting the undercut groove in the rotor in order to have a more sturdy, unitary structure. Wherever turbine blades are 30 mounted in this way, it is necessary to provide the undercut groove with a widened portion in order that the blade roots may be inserted in the groove, from which widened portion the blades are moved around the rotor to their 35 ultimate positions. Difficulties have heretofore been encountered in providing means for holding a blade mounted in the widened portion because of the high centrifugal stress to which the blade is subjected and because of the difficulty of providing adequate fastening means at the side of the blade root.

40 In accordance with my invention, I form the widened portion of the undercut groove with serrated sides and provide a locking piece at each side of the blade root and fitting

the blade root. At each outer side of the widened portion is a filling piece having serrations fitting the serrations of the widened portion. Wedges are then inserted between the locking pieces and the filling pieces firmly 45 engaging them with the side of the blade root and the widened portion. As a further means of securing the assembled structure together I drill a tapered hole common to the locking piece, the filling piece and the wedges at each 50 side of the blade and screw a tapered plug into the hole, firmly locking the assembled structure together.

Referring now to the drawings for a more detailed description of my invention I show 55 in Fig. 1 at 10 a fragment of a turbine rotor provided with an undercut groove 11, having blades 12 mounted therein. The blades 12 are provided with root portions 13, fitting the sides of the groove 11. In order that the 60 blades 12 may be inserted in the groove 11 I provide the groove with a widened portion 14 through which the blades are inserted and moved around the rotor to their ultimate 65 positions. As shown in Figs. 1 and 2 the 70 widened portion 14 of the groove 11 is adapted for the insertion of turbine blading 12 of the reaction type having a root portion 75 fitting diagonally across the groove 11. I accordingly show one side of the widened 80 portion 14 as being offset from the other in order that the holding means for the blade 85 to be mounted therein may have a better bearing on the blade root. Where blades are employed having a root portion extending 90 straight across the groove 11 it is to be understood that the widened portion 14 should be formed accordingly.

95 In order to secure a blade in the widened portion 14 after the groove 11 has been completely filled, except for the widened portion, I provide the widened portion 14 with serrations 16 which cooperate with similar serrations of a filling piece 17 and a locking piece 18 inserted at each side of the blade for holding 100 said blade in position. The locking piece 18, at one side, is provided with a projection 19 complementary in contour to the blade root 13 and is provided with serrations 21 cooperating with the serrations 16 of the widened 105 portion 14. The filling piece 17 and locking piece 18 are of such thickness that when placed in the widened portion 14 and moved as far to the side as possible, they permit the insertion of the blade root 13 into the widened 110

portion 14. After insertion of the last blade root 13 the locking pieces 18, one at each side of the blade, are moved over toward the blade so that the projection 19 engages with the 5 blade root 13. I then drive compound wedges 22 and 23 between the filling pieces 17 and the locking pieces 18, causing them to firmly engage the side of the widened portion 14 and the blade root 13. As a further means of 10 securing the filling piece 17, locking piece 18 and wedges 22 and 23 in position, I drill and thread a hole 24 into the assembled structure as shown in Figs. 2 and 3 and screw a plug 26 into the hole 24. The hole 24 and plug 26 are preferably tapered in order to provide a 15 wedging action. The plug 26 engages with the filling piece 17, compound wedges 22 and 23 and the locking piece 18, firmly locking them in position and at the same time providing further wedge means, whereby a more 20 sturdy unitary structure is obtained. After assembly the top of the tapered plug may be cut off smooth as shown in Fig. 2 and at the left in Fig. 3.

25 The outward stresses of each locking piece 18, caused by the centrifugal force of the blade or blades 12 with which it interlocks, are transmitted to the rotor 10 in two ways. A portion of the stresses is transmitted directly 30 to the circumferentially opposite sides of the widened portion 14 by the serrations 16 and 21 and another portion is transmitted through the tapered plug 26 and filling piece 17 to the outer end of widened portion 14.

35 From the foregoing it will be apparent that I have invented an improved blade fastening for securing a turbine blade in the widened portion of an undercut groove, simple of design, easy of assembly and dis-assembly and 40 which provides a sturdy unitary structure.

45 While I have shown my invention in but one form, it will be obvious to those skilled in the art that it is not so limited, but is susceptible of various other changes and modifications, without departing from the spirit thereof, and I desire, therefore that only such limitations shall be placed thereupon as are imposed by the prior art or as are specifically set forth in the appended claims.

50 What I claim is:

55 1. In a turbine, the combination of a rotor provided with an undercut groove, said groove having a widened portion for the insertion of blades in the groove, blades mounted in the groove, a blade mounted in the widened portion and having a root portion complementary to the undercut groove, a locking piece fitting the root portion of the blade, a filling piece fitting the widened portion of the groove, and wedge means between the locking piece and the filling piece for holding the locking piece, the filling piece and the blade in position.

60 2. In a turbine, the combination of a rotor having an undercut groove provided with a 65

widened portion for the insertion of blades in the groove, a blade mounted in the widened portion and having a root portion complementary to the undercut groove, locking pieces at each side of the blade and fitting the root portion thereof, filling pieces at each side of the widened portion of the groove, and wedge means between the locking pieces and the filling pieces.

75 3. In a turbine, the combination of a rotor having an undercut groove provided with a widened portion for the insertion of blades in the groove, a blade mounted in the widened portion and having a root portion complementary to the undercut groove, locking pieces at each side of the blade and fitting the root portion thereof, filling pieces at each side of the widened portion of the groove, wedges between the locking pieces and the filling pieces, and means for locking the locking pieces, the filling pieces, and the wedges in position.

80 4. In a turbine, the combination of a rotor having an undercut groove provided with a widened portion for the insertion of blades in the groove, said widened portion having serrated sides, a locking piece at the side of the blade fitting the root portion of the blade and having serrations fitting the serrations of the widened portion, a filling piece at the outer side of the widened portion and having serrations fitting the serrations of the widened portion, wedges between the locking piece and the filling piece, and a single member engaging and locking the locking piece, 90 the filling piece, and the wedges in position.

95 5. In a turbine, the combination of a rotor having an undercut groove provided with a widened portion for the insertion of blades in the groove, said widened portion having serrated sides, a blade mounted in the widened portion, a locking piece at the side of the blade fitting the root portion of the blade and having serrations fitting the serrations of the widened portion, a filling piece at the outer side of the widened portion and having serrations fitting the serrations of the widened portion, wedges between the locking piece and the filling piece, and means for locking the locking piece, the filling piece and wedges 105 in position comprising a tapered threaded plug engaging with said filling piece, the wedges and the locking piece.

110 6. In a turbine, the combination of a rotor having an undercut groove provided with a widened portion for the insertion of blades in the groove, said widened portion having serrated sides, a blade mounted in the widened portion and having a root portion complementary to the undercut groove, a packing piece at each side of the blade, fitting the root portion of the blade, and having serrations fitting the serrations of the widened portion, a filling piece at each outer side of the widened portion and having serrations fitting the 115

serrations of the widened portion, wedges between each of the locking pieces and its associated filling piece, and means at each side of the blade for locking the locking piece, the filling piece and wedges in position comprising a tapered threaded plug engaging with the filling piece, the wedges and the locking piece.

7. In a turbine, the combination of a rotor having an undercut groove provided with a widened portion for the insertion of blades in the groove, a blade mounted in the widened

portion, a locking piece at the side of the blade and having interlocking engagement therewith, a filling piece at the side of the widened portion, wedging means between the locking piece and the filling piece, and means for transmitting radial stresses from the blade through the locking piece, wedge means and filling piece to the rotor.

In testimony whereof, I have hereunto subscribed my name this second day of September, 1924.

JAMES L. RAY.
